UNITED STATES PATENT OFFICE.

MELVILLE ROSYN GRANT, OF MERIDIAN, MISSISSIPPI.

SWING ATTACHMENT.

No. 922,886.

Specification of Letters Patent.

Patented May 25, 1909.

Application filed September 23, 1908. Serial No. 454,394.

To all whom it may concern:

Be it known that I, MELVILLE R. GRANT, a citizen of the United States, and a resident of Meridian, in the county of Lauderdale and 5 State of Mississippi, have invented certain new and useful Improvements in Swing Attachments, of which the following is a specification.

This invention is an improvement in crib 10 attachments for swing seats; and the invention consists in certain novel constructions, and combinations of parts as will be herein-after described and claimed.

In the drawings, Figure 1 is a perspective 15 view of the invention as in use, the attachment being applied to one of the seats of the swing. Fig. 2 is a detail perspective view of the improvement removed from a swing. Fig. 3 is a top plan view, and Fig. 4 is a side 20 view of the attachment removed from the swing.

By my invention I provide in connection 25 with the seat A of a lawn swing, a crib attachment which may be applied to and re-moved from the seat and is constructed as shown with an intermediate or main section B, and end sections C, jointed at one end to their respective ends of their intermediate 30 section, and provided at their other or free ends with means for securing the attachment to the swing seat.

As shown the sections are formed with slats B' and C', and with end bars or battens B² and C² and C³, as best shown in Figs. 3 and 35 4, the battens B² and C² being hinged together at D, so that when the sections are opened to the position shown in Figs. 1 and 3, the said battens B² and C² will abut and 40 form stops for holding the sections B and C in expanded position.

At their free or swinging ends the sections C are provided with hooks E which engage with suitable bearings on the swing seat for holding the crib attachment to the swing in 45 the use of the invention.

As will be understood from Figs. 2 and 4, the slats C⁴ of the end sections C, are ar-ranged at an inclined angle with respect to their battens C², so that when folded as 50 shown in Fig. 1, the slats of the sections B and C are not parallel, and when opened, as

shown in Fig. 1, the sections C tend to hold the section B at an incline, thus increasing the capacity of the crib.

In applying the crib attachment to the 55 swing seat, the end sections C extend along the inner side of the side rails F of the swing, and the hanger bar G thereof is hooked into engagement with the seat in such manner as to secure a bracing of the crib attachment by 60 the portions of the swing at the ends of the swing seat.

The construction is simple and can be easily applied to and removed from the swing and efficiently serves the purpose for 65 which it is designed.

As best shown in Figs. 1, 2 and 4 I provide the crib attachment at the juncture of its main section and end sections with depending arms, which, when applied as shown in 70 Fig. 1, lap along the ends of the seat A and these arms are preferably the extended ends of the battens B² of the end sections B as shown. It will also be noticed that the bottom of the seat forms the bottom of the crib 75 and the crib extends throughout the length of the seat so that its end sections are braced by the swinging construction at the ends of the said seat. This depending arm construc-tion and the location of the end sections adja-80 cent to the upright hanger bars of the swing are correlated in that the said upright hanger bars brace the end sections against outward displacement, and the depending arms lead-ing along the ends of the seat, brace the said 85 end sections against inward movement, thus providing a construction especially useful and advantageous in swings as shown and before described.

I claim—

A swing having a seat and side bars, and upright hanger bars at the ends of said seat, and provided with a crib attachment having a main section extending between said up-right hanger bars and provided at its ends 95 with battens whose lower ends are extended downwardly alongside the ends of the swing seat and end sections hinged at one end to the ends of the main section and extending thence longitudinally at an inclined angle to 100 the axes of the hinged connection, the said end sections of the crib attachment extend-

ing along the inner side of said hanger bars and side bars and adjacent thereto whereby the crib attachment will be held in position by the engagement of the end sections along 5 the inner side of the hanger bars and side bars of the swing and by the engagement of the depending arms of the main section along

the ends of the seat, and means for fastening the crib attachment to the seat, all substantially as and for the purposes set forth.

MELVILLE ROSYN GRANT.
